US0D1050048S

(12) **United States Design Patent** (10) **Patent No.:** **US D1,050,048 S**
(45) **Date of Patent:** **** Nov. 5, 2024**

(54) **POWER STRIP**

(71) Applicant: **Shenzhen City Yuechen Technology Co., Ltd**, Guangdong (CN)

(72) Inventor: **Yuebo Tao**, Guangdong (CN)

(73) Assignee: **Shenzhen City Yuechen Technology Co., Ltd**, Guangdong (CN)

(**) Term: **15 Years**

(21) Appl. No.: **29/883,812**

(22) Filed: **Feb. 3, 2023**

(30) **Foreign Application Priority Data**

Aug. 4, 2022 (CN) 202230507313.1

(57) **CLAIM**

The ornamental design for a power strip as shown and described.

DESCRIPTION

FIG. 1 is a front, right and bottom perspective view of a power strip, showing my design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, right and bottom perspective view of a second embodiment of a power strip.

FIG. 10 is a rear, left and top perspective view of the second embodiment of the power strip of FIG. 9.

FIG. 11 is a front elevation view of the second embodiment of the power strip of FIG. 9.

FIG. 12 is a rear elevation view of the second embodiment of the power strip of FIG. 9.

FIG. 13 is a left side elevation view of the second embodiment of the power strip of FIG. 9.

FIG. 14 is a right side elevation view of the second embodiment of the power strip of FIG. 9.

FIG. 15 is a top plan elevation view of the second embodiment of the power strip of FIG. 9; and,

FIG. 16 is a bottom plan elevation view of the second embodiment of the power strip of FIG. 9.

The broken lines depict portions of the power strip that form no part of the claimed design.

1 Claim, 16 Drawing Sheets
